UNITED STATES PATENT OFFICE.

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS OF CRACKING PETROLEUM OIL.

Application filed October 27, 1923. Serial No. 671,070.

This invention relates to improvements in a process of cracking petroleum oil, and refers more particularly to that type of process in which the oil is initially passed 5 through a heating coil and thence to an expansion chamber, where a greater part of the vaporization takes place. The vapor is removed from the expansion chamber and subjected to a reflux condensing action. 10 The feature of the invention is that both the reflux condensate and the residuum are recycled so as to subject them to further reaction, but in such a way as to avoid contamination of the heating coil with the residuum thereby stopping or clogging the coil.

The invention will more particularly appear from the following description, to which is attached a drawing, the single 20 figure of which shows a somewhat diagrammatic view partly in side elevation and partly in vertical section of the apparatus.

Referring to the drawings (1) designates the furnace in which is mounted the heating 25 coil (2), which may take the form of continuous length of say 4" pipe, the oil being fed to the coil by raw oil pump (3) and feed line (4). The oil passes out of the coil through transfer line (5) and throttle valve (6) to the upper part of expansion chamber (7) which may take the form of a vertical extending shell as shown. Expansion chamber (7) is provided at its upper end with a vapor outlet pipe (8) having control valve 30 (9) and connected to a horizontal extending dephlegmator (10). Vapors pass out of the dephlegmator through vapor pipe (11) having control valve (12) to condenser coil (13) and thence through pipe (14) having control 35 valve (15) to the top of receiver (16). This receiver (16) has the gas control valve (17) and liquid control valve (18).

It is understood that these various valves are throttle valves by which the flow of the 45 liquid can be regulated.

The residuum is drawn off the expansion chamber (7) through pipe (19) through any of branch lines 19^a controlled by valves 19^b and thence recirculated by circulation pump 50 (20) and line (21) back to the transfer line (5) just before it enters the expansion chamber (7) as shown at (22). The reflux condensate is drawn off the bottom of the dephlegmator through pipe (23) having valve (24) back to the circulating pump

(20), the arrangement being such that both the reflux condensate and the residuum may be recirculated through the expansion chamber (7) and further distillation takes place; the reflux condensate and residuum being heated, of course, by the incoming raw oil.

If desired, more or less of the reflux condensate can be by-passed through branch pipe (23') by regulating valves (24), (30) and (25). Similarly, more or less of the residuum may be by-passed through branch 65 (26) by regulating valves (27) and (28).

If desired, more or less of the reflux may be fed directly and returned directly to the coil through the line (29) by suitably regulating valves (30) and (25) closing valve (24). It will be seen that by means of the present arrangement the reflux condensate and residuum may be recirculated through the expansion chamber where they will be 70 subjected to further distillation, and that the residuum is at all times kept out of contact with the raw oil in the coil (2).

In carrying out the process the raw oil may be fed through the coil to where it may 80 be heated to a temperature of 850° F. and subjected to a pressure of a hundred pounds or more, and thence delivered to the expansion chamber (7). Vapors will pass out through the dephlegmator, the heavier portion being condensed and returned to the reflux line, either to the expansion chamber, or heating coil, while the uncondensed vapors will pass to the receiver. The residuum, or such portions thereof as desired, will be 85 recirculated through the chamber (7). A uniform pressure may be maintained in the entire system, or a higher pressure maintained in the coil (2) than in the expansion chamber.

I claim as my invention:

1. A process for cracking petroleum oil consisting in passing the oil through a heating coil, where it is subjected to cracking conditions of temperature, thence to an expansion chamber removing vapors from said expansion chamber and subjecting them to a reflux condensing action withdrawing residuum from said expansion chamber and recirculating the residuum directly back 105 through said expansion chamber where it is further distilled by returning the same to the vapor space of said expansion chamber, and returning the reflux condensate to said expansion chamber for further treatment. 110

2. A process for cracking petroleum oil consisting in passing the oil through a heating coil, where it is subjected to cracking conditions of temperature, thence to an expansion chamber removing vapors from said expansion chamber and subjecting them to a condensing action withdrawing residuum from said expansion chamber and recirculating the residuum directly back through the vapor space of said expansion chamber where it is further distilled.
3. A process for cracking petroleum oil consisting in passing the oil through a heating coil, where it is subjected to cracking conditions of temperature, thence to an expansion chamber removing vapors from said expansion chamber and subjecting them to a reflux condensing action withdrawing residuum from said expansion chamber and recirculating the residuum directly back through the vapor space of said expansion chamber where it is further distilled, and returning reflux condensate to said system, for further treatment.
4. A continuous process of oil conversion, consisting in advancing a stream of oil through a heating zone wherein it is subjected to a cracking temperature, in introducing the highly heated oil into an enlarged reaction zone wherein a body of oil accumulates and substantial vaporization takes place, in dephlegmating the evolved vapors, in continuously withdrawing unvaporized residual oil from said reaction zone below the liquid level of the oil therein, and in returning such withdrawn residual oil under a mechanical pressure directly and without passing the same through the heating zone into the vapor space in said reaction zone to undergo further treatment therein, and in maintaining a self-generated superatmospheric vapor pressure on the oil in said stream and in said reaction zone.
5. A continuous process of oil conversion, consisting in subjecting an advancing stream of oil to a cracking temperature in a heating zone, in passing heated oil from said stream into an enlarged reaction chamber wherein a body of liquid oil accumulates and substantial vaporization occurs, in dephlegmating the evolved vapors, in continuously withdrawing unvaporized residual oil from said reaction zone, in isolating predetermined portions of such residual oil from the

system, in returning the remaining portion of the residual oil under a mechanical pressure directly and without passing the same through said heating zone to the vapor space of said reaction zone for further treatment, and in maintaining a superatmospheric vapor pressure on the oil in said stream and reaction zone.

6. A continuous process of oil conversion, consisting in subjecting an advancing stream of oil to a cracking temperature in a heating zone, in passing heated oil from said stream into an enlarged reaction chamber wherein a body of liquid oil accumulates and substantial vaporization occurs, in dephlegmating the evolved vapors, in continuously withdrawing unvaporized residual oil from said reaction zone, in isolating predetermined portions of such residual oil from the system, in returning the remaining portion of the residual oil under a mechanical pressure without increasing the temperature thereof, directly to the vapor space of said reaction zone for further treatment, in maintaining a superatmospheric vapor pressure on the oil in said stream and reaction zone, and in uniting reflux condensate resulting from dephlegmation of the vapors with a supply of charging stock to be introduced therewith to said stream of oil for further treatment.

7. A continuous process for converting hydrocarbon oil comprising subjecting the oil to a cracking temperature in a heating zone, introducing the heated oil into an enlarged reaction zone wherein a body of oil accumulates and substantial vaporization occurs, dephlegmating the vapors evolved from the oil, continuously withdrawing unvaporized residual oil from said reaction zone below the liquid level of the oil therein, uniting with the unvaporized residual oil withdrawn from said reaction zone reflux condensate separated from the vapors undergoing dephlegmation, returning such withdrawn residual oil commingled with reflux condensate directly and without passage through the heating zone into the vapor space in said reaction zone to undergo further treatment therein, and maintaining a superatmospheric pressure on the oil undergoing treatment in the process.

GUSTAV EGLOFF.
